(57) **CLAIM**

The ornamental design for a seatbelt latch, as shown and described.

DESCRIPTION

FIG. 1 is a perspective view of a seatbelt latch showing my new design, shown in a state of use;

FIG. 2 is an upper perspective view of the design of FIG. 1;

FIG. 3 is a lower perspective view of the design of FIG. 1;

FIG. 4 is a front view of the design of FIG. 1;

FIG. 5 is a rear view of the design of FIG. 1;

FIG. 6 is a first side view of the design of FIG. 1;

FIG. 7 is a second side view of the design of FIG. 1;

FIG. 8 is a top view of the design of FIG. 1; and,

FIG. 9 is a bottom view of the design of FIG. 1.

The broken lines in the drawings represent portions of the seatbelt latch and form no part of the claimed design. The other broken lines in FIG. 1 represent environmental subject matter only and form no part of the claimed design.

1 Claim, 9 Drawing Sheets
